UNITED STATES PATENT OFFICE.

WILLIAM F. KINNEE AND LLOYD B. KINNEE, OF MILWAUKEE, WISCONSIN.

RADIATOR.

Application filed December 1, 1927. Serial No. 236,949.

This invention relates to radiators and is particularly directed to a radiator humidifier.

In using radiators, it has been found that the wall soon becomes soiled adjacent the radiator, and in addition to this, the humidifying or moistening of the air has to be provided for by auxiliary means.

This invention is designed to provide a radiator construction, in which means are provided for moistening the air and also in which means are provided for preventing soiling of the wall.

Further objects of this invention are to provide a radiator having the characteristics noted above in which projecting lugs are provided for carrying an apron and a cover or hood, and also in which projecting portions are provided for holding a moistening pan securely in position against either lateral or longitudinal sliding, the projections serving as supports for the cover or hood.

It will be observed that the hood or cover will also serve the purpose of a seat when it is used in connection with a low radiator, and as a table or shelf when used in connection with a high radiator.

An embodiment of the invention is shown in the accompanying drawings in which:

Figure 1 is a front view of a radiator with parts broken away and in section;

Figure 2 is an end elevation with parts broken away and in section;

Figure 3 is a sectional view on the line 3—3 of Figure 1.

Referring to the drawings, it will be seen that a radiator has been provided with end members 1 and intermediate members 2. This radiator may be for hot water or steam, as desired. The radiator is also equipped with an intermediate or central member 3. The intermediate member, it will be noted, particularly from Figure 3, is provided with upstanding lugs 4, which lugs serve the purpose of an intermediate support for the hood of radiators of maximum length, and between which a water pan or humidifying pan 5 is positioned. This pan rests on the tops of all of the intermediate sections 2 and abuts upwardly projecting, relatively wide end lugs 6, carried by the end members 1, as shown in Figures 1 and 2. These end lugs 6, it will be noted, are not as narrow as the lugs 4, but are provided with inwardly bevelled or widened portions, as may

be seen from Figure 2, which engage the end corners or end portions of the pan and thus prevent the pan from slipping longitudinally.

The end members of the radiator are provided with bosses 7, as indicated in Figures 1 and 2, and the radiator is also provided with a hood or cover 9 of rectangular construction, having downwardly extending marginal flanges and having a standard filling aperture 10 provided with a hinged cover, which cover is, as shown, when closed, preferably flush with the top of the hood. The bosses 7 are provided for the purpose of allowing an air space at the end of the hood and also to prevent said cover from becoming excessively hot. Thus, these bosses engage the end marginal flanges and thereby prevent lateral movement of said cover, in addition to the functions previously mentioned.

Further, the end members 1 are provided with rearwardly projecting bosses 12 which receive screws 13, as shown in Figure 2. The bosses 12 are positioned adjacent the upper and lower ends of the members 1 and about a rear apron 14.

In the larger sized radiators having the maximum number of intermediate sections, bosses are positioned adjacent the upper and lower ends of the intermediate members, to thus hold the rear apron 14 securely in place, and providing an air space between the radiator and apron to control and direct air currents over the water pan 5 and under the hood 9.

Further, it is to be noted that the rear apron 14 is provided with forwardly turned portions 14' which form shields adjacent the rear and ends of the radiator. The apron extends downwardly below the body of the radiator and stops short of the bottom of the feet 15, as shown in Figures 1 and 2.

The hood and apron are spaced an exact distance from the radiator by the lugs and bosses described above, to secure a uniform product.

Further than this, the rear apron directs the rising air inwardly away from the wall and is itself cooled to a certain extent by this rising air, so that the heated air does not play freely against the wall at the rear of the radiator.

Further than this, the heated air sweeps across the water pan and is discharged forwardly of the radiator, thus throwing the

heated air and the moisture out into the room.

It is to be noted further that the radiator is of attractive and pleasing design as the water pan is completely covered by the hood and as the hood and apron form a unitary portion of the radiator itself.

Although the invention has been described in considerable detail, such description is intended as illustrative rather than limiting as the invention may be variously embodied and as the scope of such invention is to be determined as claimed.

We claim:

15 The combination of a radiator provided with end members and a plurality of intermediate members, one of said intermediate members having a pair of projecting spaced lugs, a water pan carried between said lugs

and resting upon the tops of said intermediate members, said end members having upwardly projecting lugs adjacent their upper ends contacting with the ends of said water pan, a rear apron spaced from, and supported by, the rear of the radiator, a 25 hood having downwardly extending marginal flanges, said radiator having bosses projecting from adjacent its upper ends and contacting with the inner portion of said hood, said apron extending upwardly and 30 under the downwardly extending marginal flanges of the hood.

In testimony that we claim the foregoing we have hereunto set our hands at Milwaukee, in the county of Milwaukee and State 35 of Wisconsin.

WILLIAM F. KINNEE.
LLOYD B. KINNEE.
